UNITED STATES PATENT OFFICE.

WILLIAM CHARLES CANDLISH, OF NEW ROCHELLE, NEW YORK, ASSIGNOR TO J. R. PALMENBERG'S SONS, INC., OF NEW YORK, N. Y., A CORPORATION OF NEW YORK.

DESIGN FOR A PEDESTAL FOR MERCHANTISE-DISPLAY FIXTURES.

Application filed May 5, 1923. Serial No. 6,085. Term of patent 7 years.

To all whom it may concern:

Be it known that I, WILLIAM C. CANDLISH, a citizen of the United States, and a resident of New Rochelle, in the county of Westchester and State of New York, have invented a new, original, and ornamental Design for a Pedestal for Merchandise-Display Fixtures, of which the following is a specification, reference being had to the accompanying drawing, forming part thereof.

The figure is a perspective view of a pedestal showing my new design.

I claim:

The ornamental design for a pedestal for merchandise-display fixtures as shown.

WILLIAM CHARLES CANDLISH.
